UNITED STATES PATENT OFFICE.

ALFRED H. DYSON, OF MONTCLAIR, NEW JERSEY, ASSIGNOR, BY MESNE ASSIGNMENTS,
TO WESTERN ELECTRIC COMPANY, INCORPORATED, A CORPORATION OF NEW YORK.

SELECTOR-SWITCH.

1,192,175.

Specification of Letters Patent. Patented July 25, 1916.

Application filed August 25, 1915. Serial No. 47,258.

To all whom it may concern:

Be it known that I, ALFRED H. DYSON, a citizen of the United States, residing at Montclair, in the county of Essex and State of New Jersey, have invented certain new and useful Improvements in Selector-Switches, of which the following is a full, clear, concise, and exact description.

This invention relates to automatic telephone switches, and particularly to multiple brush switches of the panel type such as shown in Patent No. 1,123,696.

The principal object of this invention resides in the improved means for controlling the operativeness or activity of the several brush sets carried by a single movable support.

In the drawings, Figure 1 is a side view with parts broken away, of a switch showing one form of the invention; Fig. 2 is a section on the line 2—2 of Fig. 1; Fig. 3 is a section on the line 3—3 of Fig. 1; Fig. 4 is a side view with parts broken away, of a modified form of the invention; Fig. 5 is a view of the upper end of the structure of Fig. 4 taken at right angles; Fig. 6 is a section on the line 6—6 of Fig. 5; Fig. 7 is a section on the line 7—7 of Fig. 4; Fig. 8 is a detached view of the brush selecting means; Fig. 9 is a view of the same device shown in a differently operated position; and Fig. 10 is a section on the line 10—10 of Fig. 4.

The switch disclosed in the present invention may be substantially the same as that shown in the patent above referred to, except as to the brush sets and brush selecting means.

In the present invention, no means is provided for spacing the brushes of the sets apart so that the brush set will thus be rendered inoperative. On the contrary, the several brush sets of a switch normally occupy positions slightly to one side of the corresponding rows of contacts in the terminal bank, and means are provided for rotating the brush set, which it is desired to use, into a position such that upon longitudinal movement of the brush shaft, the brushes of the set will be caused to traverse the contacts in its section of the terminal bank.

Referring to Fig. 1 of the drawings, 1 represents the brush shaft upon which is rotatably mounted a plurality of sleeves 2,

which are prevented from longitudinal movement on the shaft by means of the collars 3 and 4 fixed to the shaft. Secured to each sleeve 2 in any suitable manner is a brush set 5 which, in the present disclosure, consists of four brushes maintained in slightly spaced relation by means of the insulating blocks 6. Carried by the sleeve 2 is a disk-like member 7 provided with a pair of ratchet teeth or stops 8 and 9. Integral with the collar 3 is the member 10, one end of which is provided with a downwardly extending pin 11 which is normally engaged by the stop 8 on the disk 7 to limit the rotation of the sleeve 2 on the shaft 1. Secured to the opposite end of the member 10 is a pawl 12 arranged to engage the ratchet tooth 9 of the disk 7 to maintain the brush set in its inoperative position, such as shown in Fig. 2. Mounted about the collar 4 is a spring 13, one end of which is fixed to the collar and the other end of which is secured to a finger 14 secured to the sleeve 2 in any desired manner. This spring tends to rotate the sleeve 2, and, therefore, the brushes mounted thereon, in an anti-clockwise direction as viewed from above.

Rotatably mounted in the frame parallel to the shaft 1 is a trip rod 15, which is provided with a plurality of projecting lugs 16 arranged at progressively increasing distances above the normal positions of the rearwardly extending portions 17 of the pawls 12. The rod 15 is arranged to be rotated by means of a trip magnet 18, the armature 19 of which, on attraction, engages the lug 20 fixed to the rod 15. Also secured to the rod 15 are a plurality of lugs 21 which are so arranged that, when the shaft is in normal position, they will engage the fingers 14 on rotation of the rod 15.

The shaft 1 may be prevented from rotating during the brush selecting operation by any desired construction, such as a spline or square portion thereof, or even by means of the rectangular elevating strip 22 being engaged by one of the frame members.

The operation of this form of the invention is as follows: The shaft 1 is moved upward a number of steps corresponding to the brush which it is desired to select. This causes the portion 17 of the pawl 12 of the desired brush set to be positioned opposite the corresponding lug 16. The trip magnet 18

18 is thereupon energized, causing the rod 15 to rotate. The lug 15 engages the pawl 17, causing the retraction of said pawl and 5 the release of the desired brush set, which is then rotated in an anti-clockwise direction under the influence of its spring 13. When the brush set reaches its operative position, further movement thereof is prevented by the stop 8 engaging the pin 11. The brushes 10 of the selected set are now caused to traverse the terminals in their respective section of the bank in a manner which is clearly disclosed in the above mentioned patent. The selected brush set is returned to its normal 15 position, after the shaft 1 has been returned to normal, by again energizing the trip magnet 18, causing the lug 21 to engage the finger 14, thus rotating the brush set in a clockwise direction to its inoperative position, where it is held by the pawl 12 engaging 20 the ratchet 9.

Referring now to Fig. 4 of the drawings, the brush shaft 23 is longitudinally and rotatably mounted in the frame, and is secured 25 to the elevating bar 24 by a swiveled connection which consists of the sleeve 25 fixed to the shaft 23. The lower end of this sleeve receives the cylindrical extension 26 carried on the upper end of the bar 24. The 30 member 26 is maintained within the sleeve 25 by means of the spring fingers 27, which are secured to the bar 24 and engaged over the upper end of the sleeve 25.

Rotatably mounted on the shaft 23 between the collars 28 and 29 are a plurality 35 of sleeves 30, to each of which is insulatively secured, in any desired manner, a set 31 of brushes. Secured to the sleeve 30 is a ratchet wheel 32 arranged to be engaged by 40 the pawl 33 pivotally secured to a projection on the collar 29. A spring 34 having one end secured to the collar 29 and the other to the pawl 33, tends to urge the lower end of the pawl toward the shaft 23. Positioned 45 about the upper end of the collar 30 is a spring 35, one end of which is secured to the collar 29, the other end being secured to said sleeve. This spring tends to rotate the sleeve in a clockwise direction as viewed 50 from above.

Secured to the frame adjacent to each brush set, when in its normal position, is an arcuate cam member 36. Extending upwardly from each cam member 36 is a cylindrical portion 37, provided near the upper edge thereof with a cam-like projection 38. These cams 38 are arranged at progressively increasing distances from the pawls 33 when in their normal position, for a purpose 55 which will hereinafter appear. Also secured to the frame adjacent to each brush set, when in its normal position, is a bracket 39 provided with a pair of projections 40 and 41. Extending downwardly from each 60 ratchet wheel 32 is a pin 42, and projecting

from each collar 28 is a pin 43. The pin 42 projecting from the ratchet 32 is arranged to engage, during different portions of the operation of the switch, with the pin 43 and also with the projections 40 and 41. 70

Secured to the shaft 23 near the upper end thereof is a friction disk 44. The power drive disk 45 is arranged to be attracted into operative engagement with the disk 44 by the clutch magnet 46. Also secured to the 75 shaft 23 near the upper end thereof is a disk 47 having a serrated edge arranged to engage an anti-friction member carried at the end of an interrupter spring 48. On rotation of the shaft, the spring 48 is caused to 80 move into and out of engagement with the spring 49, causing one interruption for each brush tripping or brush selecting position of the shaft 23. Also secured to the shaft 23 near the upper end thereof is a ratchet 85 wheel 49', arranged to be engaged by the pawl 50 pivotally mounted in the lug 51 secured to the frame. When in its normal position, the upper end of the pawl 50 is engaged by a disk 52 on the shaft 23 and is thus held in its retracted position. When the shaft takes its first upward step or movement, however, the disk 52 moves from engagement with the pawl 50 and allows the pawl to be forced into engagement with the 90 ratchet wheel 49' by the spring 53.

The operation of the modification of the invention shown in Fig. 4 of the drawings is as follows: When the switch is in its normal position, the several brush sets occupy 10 a position to one side of their respective rows of terminals in the terminal bank, as illustrated in Fig. 6 of the drawing. At this time, the several pawls 33 are maintained in their retracted or inoperative position by reason of the engagement of the lower end thereof with the cam members 36. Upon operation, the switch is first moved upwardly one step. This releases the pawls 33 and allows them to come into engagement 11 with their respective ratchet wheels 32. The clutch magnet 46 is thereupon energized, causing the switch shaft to be rotated in the direction of the arrow in Fig. 4. When the shaft has been rotated a number of steps 11 equal to the number of the brush set which it is desired to select or to use, the pawl 33 of this brush set will be positioned immediately below its respective cam member 38. During this rotary movement of the shaft, 12 the brush set has been prevented from rotating by the engagement of the pin 42 with the projection 40. The brush shaft 23 is now moved upwardly another step, when the pawl 33 of the selected brush set engages 13 its cam 38 and releases the brush set. This upward movement has also moved the pin 42 from engagement with the projection 40, and the brush set is rotated by the spring 35 until the pin 42 engages the projection 14.

41, which rotation will bring the brush set into operative relation to its section of the panel bank, as shown in Fig. 10 of the drawings. Upon continued upward movement of the brush shaft, the pawl 33 of the selected brush set passes out of engagement with the cam 38 before the pin 42 passes out of engagement with the projection 41. The pawl 33 thereupon engages the ratchet wheel 32 and maintains the selected brush set in its operative position during the selecting movement of the switch. As only one of the pawls 33 engaged the cam 38, the remaining brush sets of the switch remain 10 in a position at one side of the row of terminal contacts, as shown in Fig. 6, the pawls having engaged the ratchet wheel 32 before the pins 43 were moved from engagement with the pins 42.

20 Upon restoration of the switch to its normal position in a manner similar to that shown in the patent above referred to, the disk 52 at the upper end of the shaft engages the pawl 50 and releases the shaft 23, which 25 is thereupon rotated back to its normal position by means of the spring 54, one end of which is secured to the casing 55, the other end being secured to said shaft. During this rotary movement, the pin 43, carried by 30 the collar 28, engages the pin 42 of the released brush set and rotates said set back to its normal position. This is permitted at this time as the outwardly projecting end of the pin 42 is now positioned below the inwardly extending end of the projection 40. As the shaft reaches normal, all the pawls 33 35 are retracted, but this movement is without effect at this time as the several brush sets are held rotated in their inoperative position 40 by means of the pins 43 engaging their respective pins 42.

What is claimed is:

1. In an automatic telephone switch, a longitudinally movable brush shaft, a plurality of brush sets mounted thereon, a series of stationary contacts for each brush, means normally maintaining said brushes in an inoperative position at one side of their rows of contacts, brush selecting mechanism, and means for operating said mechanism to permit a desired brush to assume its operative position.

2. In an automatic telephone switch, a longitudinally movable brush shaft, a plurality of brush sets rotatably mounted on said shaft, a series of stationary contacts for each brush, means normally maintaining said brushes in an inoperative position at one side of their rows of contacts, brush

selecting mechanism, and means for operating said mechanism to permit a desired brush to assume its operative position.

3. In an automatic telephone switch a brush shaft, a plurality of brush sets rotatably mounted on said shaft, a series of stationary contacts arranged to be traversed by each brush, a pawl and ratchet device for each brush normally maintaining said brush in an inoperative position at one side of its row of contacts, a brush tripping mechanism, and means for operating said mechanism to permit a desired brush to assume its operative position.

4. In an automatic telephone switch, a brush shaft, a plurality of brush sets rotatably mounted on said shaft, a series of stationary contact sets for each brush set, a pawl and ratchet device for each brush set normally maintaining the brushes thereof in an inoperative position at one side of their rows of contacts, a tension device for each brush set tending to rotate said set to its operative position, brush tripping mechanism, and means for operating said mechanism to retract the holding pawl of a desired brush 85 set to permit said set to assume its operative position.

5. In an automatic telephone switch, a brush shaft, a plurality of brush sets rotatably mounted on said shaft, a series of stationary contacts for each brush, means normally maintaining said brushes in an inoperative position at one side of their rows of contacts, means for rotating said shaft, means for moving said shaft longitudinally, 95 and means dependent on the degree of rotation of said shaft prior to the longitudinal movement thereof for selecting a desired brush set.

6. In an automatic telephone switch, a brush shaft, a plurality of brush sets rotatably mounted on said shaft, a series of stationary contacts for each brush, a holding pawl for each brush normally maintaining said brush in an inoperative position at one 105 side of its row of contacts, a tension device for each brush tending to rotate it to its operative position, means for rotating said shaft to select a desired brush set, and means operated by the subsequent longitudinal 110 movement of said shaft for actuating the holding pawl of the selected brush to permit said brush to assume its operative position.

In witness whereof, I hereunto subscribe my name this 21st day of August A. D., 115 1915.

ALFRED H. DYSON.
